R. F. A. MEYER,
DOOR AND WINDOW LOCK,
APPLICATION FILED JAN. 11, 1922.

1,426,896.

Patented Aug. 22, 1922.

UNITED STATES PATENT OFFICE.

ROBERT F. A. MEYER, OF NEW YORK, N. Y.

DOOR AND WINDOW LOCK.

1,426,896.

Specification of Letters Patent. Patented Aug. 22, 1922.

Application filed January 11, 1922. Serial No. 528,407.

To all whom it may concern:

Be it known that I, ROBERT F. A. MEYER, a citizen of the United States, residing at New York, in the county of New York and State of New York, have invented certain new and useful Improvements in Door and Window Locks, of which the following is a specification.

This invention relates to locks used in connection with doors and windows, the main object being to provide a lock which will permit a door or window to be partly open and still remain locked so that a person on the outside of the house cannot open the same farther.

Another object is to provide a device as described having a special type of key by which the lock can be sprung open after the person has inserted the key in its proper place, this being accomplished while the door stands slightly ajar.

Still another object is to provide a lock especially useful where constant ventilation is desirable, without opening the premises to persons not having the proper authority.

These and other objects will become apparent in the description following in which reference characters refer to the like-named parts in the drawing.

Briefly describing the drawing, Figure 1 represents a fragmentary front elevation of a door and sash having the device in the locked position thereon.

Figure 2 is a side elevational section taken on line 2-2 of Figure 1.

Figure 3 is a side elevation of the same but looking at the lock from the bottom.

Figure 4 is a plan view of the removable key.

Figure 5 is a cross section taken on line 5-5 of Figure 1 and shows the key member in position for permitting the door to be opened. The broken lines in this view represent the position of the door, with respect to the sash, when the key is placed in position.

Describing the drawing in detail, the numeral 10 indicates the sash end 11 the door of a standard form of construction used generally on all buildings. A plate 12 is se-

cured on the interior surface of the door 11 by screws 13 and has an angular bracket 14 projecting therefrom and extending over the sash somewhat. A substantially rectangular plate member 15 is permanently secured to the sash 10 by screws 16, and has ears 17 located centrally thereon, forming a pivot

bracket for the main locking plate 18 through the medium of pin 19.

An elongated knob 20 formed on the end of member 14 has a slightly smaller neck beneath the latter and is adapted to ride in slot 21 of plate 18. Figures 1 and 2 represent the door and sash members in interlocked position. The door may be opened by swinging plate 18 into the position illustrated by dotted lines in Figure 1; and simultaneously rotating the door. A spring 22 secured to the side of one of the ears 17 has ball-shaped stops 22^a riveted thereto, the latter urging the locking plate 18 into interlocking position when said plate is vertically suspended. Ridges 23 form stop guides for the locking plate and retain the same in contact with part 20 when the door is closed.

The closing and locking of the door is accomplished in the usual manner, the knob 20 meanwhile riding upon wing 25 and forcing the plate 18 outward until slot 21 of the latter engages the knob 20. The door is unlocked in this position but since knob 20 is in slot 21 of plate 18, opening the door to any extent will rotate plate 18 in such manner that the ends 24 of knob 20 will project over the slot and interlock both members with each other. The dotted lines in Figure 2 illustrate the knob 20 entering an interlocking position while plate 18 is being rotated upwardly, the limit of opening the door being reached, when the end of slot 21 reaches the level of arm 14.

A means for opening the door from the outside is provided by a key 29 having a hole 26 which slips over the pin 27 fixed to the lower end of plate 12. In opening the door after being slightly set ajar, key 29 is placed on pin 27 and permitted to extend angularly so that the notch 28 engages the edge of 18, and the door then closed. In closing, key 29 will describe an arc about pivot pin 27, member 29 riding in notch 28 will be forced out of engagement with knob 20 after which the door can be opened or closed at will. It is to be noted that, after placing the key in proper position, it is necessary to close the door to operate the key 25.

I claim:

1. A lock of the class described comprising a vertical plate secured to a door sash, ears formed on said plate, a slotted locking plate pivotally secured between said ears, an angular bracket secured to the door within the sash engaging said slotted plate, a spring

stop secured to the ears and adapted to urge the slotted plate into engagement with said bracket when the slotted plate is in vertical position, means for interlocking said angular bracket and said slotted plate on opening movement of the door and means for releasing the lock from without.

2. A lock of the class described comprising an angular bracket secured to a door, an 10 elongated knob formed on the end thereof, a plate member secured to the door sash and having ears formed thereon, a slotted locking plate pivoted between said ears, a spring stop urging the locking plate into engagement with said knob, said knob adapted to shoulder in the slot of the locking plate when partly open and means for disengaging the door bolt from the locking plate by 15 closing the door.

3. A lock of the class described comprising an angular bracket secured to a door, an elongated knob on the end of said bracket, a slotted locking plate pivotally mounted on the door sash and adapted to releasably engage the knob end of said bracket, when in 20 the vertical position, a spring stop urging the locking plate into engagement with said bracket, a key member, a pivot stud secured to the sash and adapted to receive the key member, a notch formed on said key engaging the edge of the locking plate and urging the latter out of engagement with the door stud simultaneously with the closing of the door, and means for interlocking the door stud with the locking plate when in the un- 25 30 35 locked position.

In witness whereof I affix my signature.
ROBERT F. A. MEYER.
